APPARATUS FOR PROCESSING A THREAD

Irvin Wizon, Springdale, Conn., assignor to American Cyanamid Company, New York, N. Y., a corporation of Maine

Application November 15, 1952, Serial No. 320,696

12 Claims. (Cl. 34—68)

This invention relates to certain new and useful improvements in apparatus for processing a thread or continuous filament (including both mono- and multifilament), and especially a thread or filament formed of synthetic material, specifically one which is constituted essentially of a polymer of acrylonitrile. More particularly the invention is concerned with certain improvements in a portion of the apparatus disclosed in Cresswell and Wizon Patent Nos. 2,558,733, dated July 3, 1951, and 2,614,289, dated October 21, 1952, the latter patent maturing from an application that was filed as a division of the application that matured into the earlier patent.

The aforementioned Cresswell and Wizon patents are directed to a process (2,558,733) and apparatus (2,614,289) for the production of flexible, synthetic, elongated articles such, for example, as continuous filament yarns or threads, and especially those formed of homopolymeric or copolymeric acrylonitrile. One embodiment of the disclosed and claimed process invention is directed to the continuous production of such articles. Certain steps of this process are concerned with the continuous drying of advancing helices of a gelled fiber or filament while the fiber is under tension, after which it is continuously passed, while relaxed and free to contract linearly, through a heated zone under certain particular conditions of time and temperature. Apparatus suitable for carrying out this process is shown in Fig. 3 of each of the aforementioned Cresswell et al. patents, this particular apparatus being broadly and specifically claimed in Patent No. 2,614,289.

It will be noted from an inspection of Fig. 3 of each of these Cresswell et al. patents that the wet or gelled filament or thread is continuously dried while it is advancing, under tension, in a helical path from the feed-on end to the take-off end of a pair of spaced, cylindrical, converging drying rolls; and that the dried thread is then passed from the discharge or take-off end of the said rolls through a heat-treating or so-called "relaxation" furnace, which is separate from the said rolls, and through which the thread is passed while it is relaxed and free to contract linearly in order further to enhance its useful properties.

It is a primary object of the present invention to provide certain new and useful apparatus improvements in a machine for the production of continuous-filament yarn or thread.

Another object of the invention is to provide a thread guide of improved design, and especially one which is adapted to be incorporated in a machine of the kind identified in the preceding paragraph.

Still another and important object of the invention is to provide an improved apparatus for the treatment of a wet thread (including a gelled thread) whereby more satisfactory and effective operations are effected, thread damage is obviated or minimized, and threads having more uniform properties are obtained.

Another object of the invention is to provide apparatus of the aforementioned kind and which additionally permits quickly removing "wrap-ups" from drying rolls so that

2

damage to the roll-assembly is avoided and operations can be quickly resumed.

Other objects of the invention will be apparent to those skilled in the art as the description of the invention proceeds.

The novel features of my invention are set forth in the appended claims. The invention itself, however, will be understood most readily from the following detailed description thereof when considered in connection with 10 the accompanying drawing which is illustrative thereof and in which

Fig. 1 is an end view of apparatus embodying my invention;

Fig. 2 is a somewhat diagrammatic side elevation of 15 the apparatus illustrated in Fig. 1, a portion thereof being shown as broken away;

Fig. 3 is a perspective view, pulled apart for purpose 20 of clarity, of a portion of the apparatus shown in Figs. 1 and 2 and illustrative of one form of a device embodied in the present invention;

Figs. 4 and 5 are elevational views, in two different 25 positions, of the device shown in Fig. 3;

Fig. 6 is an elevational view of another form of device embodied in the present invention; and

Fig. 7 is an exploded, perspective view, partly broken away, of the device shown in Fig. 6.

One of the problems encountered in the practicing of the process carried out by the use of, for example, apparatus of the kind illustrated in Fig. 3 of the aforementioned Cresswell et al. patents has been the difficulty in maintaining the dried thread in a fixed position during its passage, while relaxed and free to contract linearly, through the heat-treating furnace or zone. This has resulted in non-uniform heat treatment and consequent irregularity in shrinkage and elongation characteristics, and in other properties, of the heat-treated thread. Also, difficulties have arisen and machine damage has resulted from "wrap-ups" of the thread during drying, caused by breaking of filaments or threads either during running operations or when starting up the machine. These latter difficulties have been due largely to the fact that the assembled or wrapped-up helices or bands of thread could not be removed quickly enough from the rolls to eliminate the tension that built up. Sometimes this built-up tension resulted in damage to the machine, especially to the shafts supporting the rolls. These and other difficulties in the operation of a continuous-spinning machine of the kind described in the aforementioned Cresswell et al. patents, and especially that portion thereof which has to do with the continuous drying of advancing helices of the thread under tension followed by continuous heat treatment of the dried thread in a relaxed state, are obviated by means of the apparatus of the present invention.

In using the apparatus of my invention a wet thread, 55 for example a gelled thread of a polymer of acrylonitrile of the kind described in the aforementioned Cresswell et al. patents, is caused to move continuously under tension through a helical path having a multiplicity of turns by feeding the thread to the feed-on end of a pair of spaced, 60 converging drying rolls. The wet thread is dried as it advances continuously under tension over the surfaces of these rolls, after which the dry thread, while relaxed and free to contract linearly, is continuously passed through another heating zone. These steps just briefly described, 65 and the apparatus employed in performing them, are essentially the same as those set forth in the aforesaid Cresswell et al. patents, and are incorporated in the specification of this application by this reference thereto. This process is improved to secure better and more uniform operating results, and more uniform thread, by my invention and which is based on my discovery that the afore-

described difficulties could be obviated by maintaining the thread in a fixed position during its passage through the heat-treating zone or furnace in a relaxed state, more particularly by controlling the rate of feed of the dry thread to the said zone or furnace while it is still under tension. In other words, by means of my invention, the thread is prevented from any substantial deviation from a fixed position, with respect to the walls defining the heat-treating zone or furnace, while the thread is continuously passing through the said zone or furnace in a relaxed state.

Referring now to the drawing and more particularly to Figs. 1 and 2 thereof. The apparatus there shown is suitable for use in continuously drying a wet thread and comprises rotatable drying means including two positively driven drums or rolls 10 and 12, suitably spaced from each other, e. g., 6 or 8 inches or more, suspended in the same plane (preferably in the same vertical plane), and rotating at the same peripheral speed. The rolls converge toward each other at the delivery end thereby to advance the thread over the rolls. The degree of convergency, which has been somewhat exaggerated for purpose of clarity in Fig. 2, may be varied as desired or as conditions may require in order to advance the thread in a plurality of helices over the rolls. Both rolls may converge slightly toward each other at the delivery end with the axis of each inclined to the horizontal or with the axis of one inclined to the horizontal while the other is horizontal.

The angle of convergency formed between the drying rolls at the take-off end cannot be specified with exactness, since it is dependent upon various influencing factors such, for example, as the diameters of the drying rolls, the distance or space between the rolls, and the thickness or diameter of the wet thread, e. g., stretched, gelled fiber or filament formed of a polymer of acrylonitrile, which is fed to the rolls. For usual operations, however, the angle of convergency of the drying rolls may range, for instance, from 0.1° to 2°. The following is a more specific example of a suitable angle of convergency of the drying rolls, as well as a suitable angle of convergency of liquid-treating rolls which are employed in a continuous-spinning machine of the kind shown in Fig. 3 of the aforementioned Cresswell et al. patents and of which the present invention embraces an improvement:

With liquid-treating rolls 4 inches in diameter, 13 inches long and on 7-inch centers at the back (feed-on end), an angle of convergency of 3° 1' at the take-off end is useful in combination with drying rolls, 4 inches in diameter, 12 inches long, on 6½ inch centers at the back (feed-on end) and adjusted to an angle of convergency of 31' at the take-off end. Such angles of convergency and difference between the angles of the respective liquid-treating and drying rolls are suitable for use in spinning a fiber of an acrylonitrile polymerization product, as described more fully in the aforementioned Cresswell et al. patents, which fiber, after being stretched about, for example, 600 to 1000%, yields a final fiber (dried and further heat-treated fiber) having a denier within the range of about 50 to about 400.

If desired, the rolls 10 and 12 may be tilted at a suitable angle to the horizontal, e. g., at an angle of approximately 5° to the horizontal. Either or both of the rolls may be heated by any suitable means. For example, the rolls may be heated and the advancing thread dried by blowing a blast of hot air or other hot gas over the surfaces of either or both of the rolls. Preferably, however, either or both rolls are hollow and are internally heated so as to provide a surface temperature which will dry the wet thread before it reaches the discharge or take-off end of the rolls. In the case of drying a continuous gelled thread of a polymer of acrylonitrile, the rolls are preferably internally heated so as to provide a surface temperature on the exterior of the rolls within the range of about 40° C. to about 200° C., more particularly within the range of about 50° or 60° C. to 100° or 120° C. Thus, either or

both of the hollow rolls or drums 10 and 12 may be internally heated electrically, or by steam, hot air or other gas, hot water or by any other suitable means. Preferably the drying unit, including the rolls and heating elements thereof, are constructed in the manner described and claimed in the copending application of Victor G. Forzley and Mario Sonnino, Serial No. 233,154, filed June 23, 1951, now Patent No. 2,622,182, dated December 16, 1952.

10 If the wet thread which is being dried on the rolls 10 and 12 is one which normally tends to accumulate a static charge of electricity while the thread is advancing and drying during its passage in the form of advancing helices over the rolls, then an antistatic finishing composition is applied to the wet thread by suitable means, e. g., in the manner described in the aforementioned Cresswell et al. patents.

15 The wet thread 14 advances under tension in a helical path, from the feed-on or rear end of the drying unit comprising rolls 10 and 12 toward the take-off or forward end thereof.

20 From the take-off or discharge end the dry, relaxed thread 16 is led, while free to contract linearly, through the heat-treating furnace 18. For information on the construction of this furnace and means employed 25 to effect relaxation of the thread during its passage therethrough, reference is made to the aforementioned Cresswell et al. patents. See these patents, also, for information as the time and temperature of thus heat-treating a dry thread formed of a polymer of acrylonitrile while it is relaxed and free to contract linearly. A preferred heat-treating or relaxation furnace is disclosed and claimed in the copending application of Mario Sonnino and Victor G. Forzley, Serial No. 315,338, filed October 17, 1952, now Patent No. 2,688,067, dated August 31, 1954.

30 In the furnaces used in continuously heat-treating a running thread in relaxed state, the thread is generally passed through a slot, the walls of which are electrically or otherwise heated.

35 Deviations in the position of the running thread, with respect to the heated walls defining the slots or zone, of about 1½ of an inch in some cases or as little as about ½ of an inch in other cases can cause non-uniform results, the permissible degree of deviation (without adversely affecting the results) depending upon such influencing factors as the chemical

40 constitution of the thread being heat treated and the temperature of the adjacent walls. The present invention prevents the thread from any substantial deviation from a fixed position, with respect to the walls defining the slot 20, while it is passing through the heated slot, and provides positive control of its relative position

45 therein.

50 The aforementioned results are obtained by the use of a suitable thread-guide unit or assembly, e. g., the unit or assembly 22 (Figs. 1 to 5, inclusive); or advantageously, for reasons later given herein, a unit of the kind illustrated in Figs. 6 and 7.

55 During operation of the apparatus the thread guide 24, which advantageously is provided with the head 26, maintains contact with the dry, tensioned thread 28 on one 60 side of the spaced rolls 10 and 12, and keeps it in a fixed position with respect to its point of discharge, in a relaxed state, from the opposite side of said rolls. The thread guide 24 is located adjacent the take-off end of the spaced rolls 10 and 12 at a point where it will contact only the last run of the dry thread before it leaves the said rolls. Advantageously the thread guide is held by a support which is positioned between the upper roll 65 10 and the lower roll 12 as shown in Figs. 1 and 2.

70 The thread guide 24 is made of any suitable smooth, tough, relatively heat-resistant material such as ceramic material or a synthetic resin, e. g., polymeric tetrafluoroethylene which is available under the trade name of Teflon. The remainder of the device, as well as that shown in Figs. 6 and 7, is advantageously made of metal, e. g., steel.

The thread guide 24 is held rigidly in position in the base 30, which is pivotally mounted on the support 32. The base 30 is provided with the opening 34 through which passes the support 32, the latter preferably being cylindrical in shape. The base is mounted on the support 32 between a front collar 33 (Fig. 2), which is rigidly but removably attached to the said support, and a similarly attached rear collar 36. Stop 38 in the base 30 and pins 40 and 42 which are fixed as indicated in the rear collar 36 maintain the guide 24 in its normal operating position as indicated in Figs. 1 and 2, and restrict its movement when it is swung to a non-operating position as indicated in dotted lines in Figs. 1 and 3 and as further shown in Fig. 5.

The thread-guide unit or assembly shown in Figs. 6 and 7 represents another embodiment of the present invention, and has certain advantages over the embodiment shown in Figs. 1 to 5, inclusive. This is because the construction is such that the thread guide 44 is held in a base 46, which latter in turn is pivotally mounted in the support 48, as is clearly illustrated in the exploded, perspective view shown in Fig. 7. The thread guide 44 is swung backward when it is in a normal operating position, its backward movement being restricted by the stop 50. When the guide is swung forward, its further forward motion is restricted by the stop 52.

Use of the thread-guide unit illustrated in Figs. 6 and 7 obviates the difficulties and machine damage that sometimes occur from "wrap-ups," as has been mentioned hereinbefore. With the device shown in Figs. 6 and 7, the banded together threads or wraps will force the guide 44 forward out of the way, thereby permitting rapid removal of the bands from the rolls. In this way there is provided an automatic safety feature which is not afforded by the thread-guide unit illustrated in Figs. 1 to 5, inclusive.

I claim:

1. Apparatus suitable for use in continuously drying a wet thread comprising rotatable drying means including a pair of spaced, converging, drying rolls adapted to receive and support the wet thread at the feed-on end and to advance it, while under tension, in a helical path toward the take-off end; and a thread guide which, in operation, maintains contact with the dry thread on one side of the said spaced rolls and keeps it in a fixed position with respect to its point of discharge, in a relaxed state, from the opposite side of said rolls, said thread guide being located adjacent the take-off end of the said rolls at a point where it will contact only the last run of the dry thread before it leaves the said rolls.

2. Apparatus as in claim 1 wherein the drying rolls are spaced, converging, drying rolls which are suspended in the same vertical plane.

3. Apparatus as in claim 1 wherein the drying rolls are spaced, cylindrical, converging, drying rolls which are suspended in the same vertical plane, and the thread guide is held by a support which is positioned between said rolls.

4. Apparatus suitable for use in continuously drying a wet thread comprising rotatable drying means including a pair of spaced, converging, drying rolls adapted to receive and support the wet thread at the feed-on end and to advance it, while under tension, in a helical path toward the take-off end; and a thread-guide unit comprising a support, a base pivotally mounted on said support between a front collar and a rear collar each of which is rigidly but removably attached to said support, said base being provided with an opening through which said support passes, a thread guide held rigidly in position in said base, a stop in said base, and at least two pins in said rear collar, said stop and pins being so positioned that the said stop and one of said pins can maintain the said guide in its normal operating position, and the said stop and another of said pins restricting the movement of said guide when it is swung to a non-operating position.

of said guide when it is swung to a non-operating position, said thread guide, when in operation, maintaining contact with the dry thread on one side of the said spaced rolls and keeping it in a fixed position with respect to the point of discharge, in a relaxed state, from the opposite side of said rolls.

5. Apparatus comprising, in combination, rotatable drying means including a pair of spaced, converging, drying rolls adapted to receive and support a wet thread at the feed-on end and to advance it, while under tension, in a helical path toward the take-off end; a heat-treating furnace in operative relationship with the take-off end of said drying rolls and which is adapted to receive the dry thread for passage therethrough in a relaxed state, said furnace being separate from the said drying rolls; and a thread guide which, in operation, maintains contact with the dry thread on one side of said spaced rolls and keeps the said thread in a fixed position with respect to the said furnace when it leaves the opposite side of the said rolls in a relaxed state, said thread guide being located adjacent the take-off end of the said rolls at a point where it will contact only the last run of the dry thread before it leaves the said rolls.

6. Apparatus as in claim 5 wherein the drying rolls are spaced, converging, drying rolls which are suspended in the same vertical plane.

7. Apparatus as in claim 5 wherein the thread guide is held by a support which is positioned between the drying rolls.

8. Apparatus as in claim 5 wherein the drying rolls are spaced, cylindrical, converging, drying rolls which are suspended in the same vertical plane, and the thread guide is held by a support which is positioned between said rolls.

9. A thread-guide unit comprising a support, a base pivotally mounted on said support between a front collar and a rear collar each of which is rigidly but removably attached to said support, said base being provided with an opening through which said support passes, a thread guide held rigidly in position in said base, a stop in said base, and at least two pins in said rear collar, said stop and pins being so positioned that the said stop and one of said pins can maintain the said guide in its normal operating position, and the said stop and another of said pins restricting the movement of said guide when it is swung to a non-operating position.

10. Apparatus suitable for use in continuously drying a wet thread comprising rotatable drying means including a pair of spaced, converging, drying rolls adapted to receive and support the wet thread at the feed-on end and to advance it, while under tension, in a helical path toward the take-off end; and a thread-guide unit comprising a support having a front stop and a rear stop, a base, means for pivotally mounting said base on said support, a thread guide held rigidly in position at the front end of said base, the backward movement of the said guide being restricted by the said rear stop when the said guide is in normal operating position, and the forward movement of the said thread guide being restricted by the said front stop when the said guide is swung forward, said thread guide, when in operation, maintaining contact with the dry thread on one side of the said spaced rolls and keeping it in a fixed position with respect to its point of discharge, in a relaxed state, from the opposite end of said rolls.

11. Apparatus comprising, in combination, rotatable drying means including a pair of spaced, converging, drying rolls adapted to receive and support a wet thread at the feed-on end and to advance it, while under tension, in a helical path toward the take-off end; a heat-treating furnace in operative relationship with the take-off end of said drying rolls and which is adapted to receive the dry thread for passage therethrough in a relaxed state, said furnace being separate from the said drying rolls; and a thread-guide unit comprising a sup-

port, a base pivotally mounted on said support between a front collar and a rear collar each of which is rigidly but removably attached to said support, said base being provided with an opening through which said support passes, a thread guide held rigidly in position in said base, a stop in said base, and at least two pins in said rear collar, said stop and pins being so positioned that the said stop and one of said pins can maintain the said guide in its normal operating position, and the said stop and another of said pins restricting the movement of said guide when it is swung to a non-operating position, said thread guide, when in operation, maintaining contact with the dry thread on one side of the said spaced rolls and keeping it in a fixed position with respect to the point of discharge, in a relaxed state, from the opposite side of said rolls.

12. Apparatus comprising, in combination, rotatable drying means including a pair of spaced, converging, drying rolls adapted to receive and support a wet thread at the feed-on end and to advance it, while under tension, in a helical path toward the take-off end; a heat-treating furnace in operative relationship with the take-off end of said drying rolls and which is adapted to receive the dry thread for passage therethrough in a relaxed state, said furnace being separate from the said drying rolls; 25

and a thread-guide unit comprising a support having a front stop and a rear stop, a base, means for pivotally mounting said base on said support, a thread guide held rigidly in position at the front end of said base, the backward movement of the said guide being restricted by the said rear stop when the said guide is in normal operating position; and the forward movement of the said thread guide being restricted by the said front stop when the said guide is swung forward, said thread guide, when in operation, maintaining contact with the dry thread on one side of the said spaced rolls and keeping it in a fixed position with respect to its point of discharge, in a relaxed state, from the opposite end of said rolls.
